UNITED STATES PATENT OFFICE.

ELEAZER KEMPSHALL, OF NEWTON, MASSACHUSETTS, ASSIGNOR TO
THEOPHILUS KING, TRUSTEE, OF BOSTON, MASSACHUSETTS.

DESIGN FOR A LACING-HOOK.

SPECIFICATION forming part of Design No. 25,863, dated August 4, 1896.

Application filed November 13, 1896. Serial No. 568,857. Term of patent 14 years.

To all whom it may concern:

Be it known that I, ELEAZER KEMPSHALL, of Newton, in the county of Middlesex and State of Massachusetts, have invented and produced a new and original Design for Lacing-Hooks, of which the following is a specification.

This invention relates to a new and original design for lacing-hooks; and it consists in the novel features of shape and configuration hereinafter fully described and particularly claimed, and clearly illustrated in the drawings.

Reference is to be had to the accompanying sheet of drawings, forming a part of this application, wherein like characters are used to indicate like parts wherever they occur.

Figure 1 is a perspective view showing my design. Fig. 2 is a longitudinal sectional view thereof.

The essential feature of my design consists in a head having a concave upper side and a convex under side, said head being concavo-

convex in cross-section and connected by a neck with a securing member. 25

a represents the head of the hook, *b* its securing member, and *f* the neck that connects the head with the securing member. The head *a* is dish-shaped, having a concave upper side, a convex lower side, and being concavo-convex in cross-section. The securing member *b* is formed of one or more parts joined together, and connected to the head by a neck *f*, the head being arranged with its convex side toward the securing member *b*. 30 35

I claim—

The design for a lacing-hook, substantially as shown and described.

In testimony whereof I have signed my name to this specification, in the presence of two subscribing witnesses, this 30th day of October, A. D. 1895.

ELEAZER KEMPSHALL.
